UNITED STATES PATENT OFFICE.

LEWIE W. HARDAGE, OF NASHVILLE, TENNESSEE.

THIGH PROTECTOR OR GUARD FOR FOOTBALL PLAYERS.

Application filed July 7, 1926. Serial No. 120,949.

This invention relates to new and useful improvements in thigh protectors or guards for football players.

Amongst the several objects of my invention are to provide a pneumatic thigh encircling guard which will protect the wearer from injury; to provide such a guard from moisture-proof material whereby moisture or perspiration will not be absorbed thereby; to provide such a guard from superposed sheets of non-porous material having their marginal edges sealed and having the sheets sealed at spaced points intermediate the edges to form communicating air channels; to provide the outer face of the guard with a plate of relatively stiff material whereby any and all impacts will be distributed over the inflated air passages of the guard and thereby protect the player from the direct impact; to provide such a guard with elastic fastening means at opposite edges, and to provide means for attaching the guard to the football trousers.

With these and other objects in view which will more fully appear the nature of the invention will be more clearly understood by following the description, the appended claims, and the several views illustrated in the accompanying drawings, in which

Figure 1 is a perspective view of a pair of football trousers equipped with my invention;

Figure 2 is a horizontal sectional view taken through one of the thigh guards,

Figure 3 is a plan view of one of the guards,

Figure 4 is a detailed sectional view taken on line 4—4 of Figure 1,

Figure 5 is a detailed sectional view taken on line 5—5 of Figure 1, and

Figure 6 is a detailed sectional view taken of the guard showing the air inlet tube.

Like numerals designate corresponding parts throughout the several figures of the drawings.

Referring to the accompanying drawings, A indicates a pair of football trousers including leg portions 5—5 and a waist portion 6.

Associated with each leg portion 5 and preferably attached to said portion, by a means hereinafter described, is a thigh protector or guard B.

Each guard comprises superposed sheets 7 and 8 of non-porous material which preferably includes a rubber base. These sheets

7 and 8 have their marginal edge portions sealed, preferably by vulcanizing. These sealed marginal edge portions are indicated by the numerals 9, 10, 11 and 12 respectively, the sealed portions 9 and 10 extending longitudinally or vertically, the sealed portion 11 extending along the bottom and horizontally and the sealed portion 12 extending generally in a horizontal direction along the top. The lower edge of the guard preferably extends along a straight line, whereas the upper edge of the guard preferably prescribes a substantially compound curve in order to fit the leg of the wearer and at the same time cover a maximum amount of the thigh. The vulcanized or sealed portions 9, 10, 11 and 12 are relatively wide in order to form flat marginal edge portion. The sheets 7 and 8, intermediate the marginal sealed edge portions, are also sealed, preferably by vulcanizing, along spaced parallel lines as indicated by the numerals 13, 14, 15, 16, 17 and 18 to provide resultant air passages 19, 20, 21, 22, 23, 24, and 25. The vulcanized lines 13 to 18 inclusive preferably extend from the top marginal sealed portion 12 downwardly towards, but in spaced relation to, the bottom sealed marginal edge portion 11 to form resultant air passages 26, 27, 28, 29, 30 and 31 which afford open communication between all of the air channels 19 to 25 inclusive.

Communicating with the upper end of one of the air channels, preferably the channel 19, is an air inlet valve 32 which may be of any suitable construction but which is preferably formed of a flexible rubber tube adapted to be folded over and tied after the guard has been inflated. The valve 32 projects outwardly from the air channel 19 and is protected against damage by ears 32^a—32^a which extend on opposite sides thereof and are formed integral with the sheets 7 and 8.

Fastening means are provided with each guard for adjustably securing the guard to the leg of the wearer. To this end, the flat sealed marginal portion 9 is provided with a plurality of eyelets 33, and an elastic strip 34 is secured by any suitable means to the opposite flat marginal edge portion 10, the outer edge portion of the strip 34 being provided with a plurality of eyelets 35. A lace 36 is associated with the eyelets 33 and 35 for adjustably securing the guard to the leg of the user.

In order to provide means for distribut-

ing an impact over the several air channels 19 to 25, I have provided a plate 41 of relatively stiff material, preferably fibre board. This plate is positioned against the outer 5 face of the guard and is permanently secured thereto by upper and lower rivets 37 and 38, as particularly shown in Fig. 4. The plate is curved horizontally to fit the leg of the wearer. The guard together with its attached 10 distributing plate 41 may be permanently attached to the leg of the football trousers by means of lower and upper eyelets 39 and 40 which are respectively secured to the lower and upper marginal portions 15 11 and 12 of the guard, as shown more particularly in Fig. 5.

The guard is positioned on the corresponding leg in such a manner that the distributing plate 41 is located partially on the front and 20 partially on the outer side of the leg or thigh, and the lower rear portion of the plate 41 is cut away as at 42 to afford freedom for leg movement of the player.

It is of course to be understood that the 25 details of structure and arrangements of parts may be variously changed and modified without departing from the spirit and scope of my invention.

I claim:

- 30 1. A pneumatic protector for football players comprising a guard formed of superposed sheets of non-porous elastic material, the sheets being sealed along their edges and also sealed at spaced points intermediate the edges to form communicating air channels, a valve connected to the guard and communicating with one of said air channels, a plate of stiff material positioned against the outer face of the guard, and means securing the plate to the guard at points along the upper and lower sealed edge portions of the guard.
- 35 2. A thigh protector for football players comprising a pneumatic thigh encircling guard in combination with a plate of stiff material secured to the outer side edge of the guard, a plurality of eyelets secured to the other side of the guard, a plurality of eyelets secured to the outer side edge of the elastic strip, and a lacing threaded through said eyelets for adjustably securing the guard in position.
- 40 3. A thigh protector for football players comprising a pneumatic thigh encircling guard in combination with a plate of stiff material secured to the outer face of the guard, the lower edge of the plate being cut away to afford freedom of leg movement to the wearer.
- 45 4. A pneumatic thigh protector for football players comprising a guard formed of superposed sheets of non-porous elastic material, the sheets being sealed along their edges and also sealed at spaced points intermediate the edges to form communicating air channels, a valve connected to the guard and communicating with one of said air channels, a plate of stiff material positioned against the outer face of the guard, and means securing the plate to the guard at points along the upper and lower sealed edge portions of the guard.
- 50 5. The combination with a pair of football trousers having leg portions, of a pneumatic thigh protector attached to each leg portion, and a plate of stiff material positioned against the outer face of each protector and attached to said protector.

In testimony whereof, I have hereunto subscribed my name.

LEWIE W. HARDAGE.
